UNITED STATES PATENT OFFICE

FREDERICK KOHNLE, OF DAYTON, OHIO, ASSIGNOR TO THE MONARCH MARKING SYSTEM COMPANY, OF DAYTON, OHIO, A CORPORATION OF OHIO

PRICE-MARKING TAG

Application filed January 6, 1928. Serial No. 245,012.

This invention relates to improvements in price marking tags or tags of similar character, and in particular to the type shown in a prior patent issued to me July 5, 1921, No. 1,383,641.

In this type of tag the attaching means comprises a soft metal wire in the form of a hook clip extending from one edge of the tag to receive and be engaged over an edge of the fabric to be tagged and bent with the lap folding of the fabric upon itself tucking the hook of the clip within the folds of the fabric, attaching the tag without pricking the goods. These tags are used for classes of merchandise which would be injured or damaged by the use of a pin type of fastener which usually pierces through the goods for attaching the tag.

The present method relates to the method of anchoring the wire clip ends wholly within the interior of the tag body or between ply layers thereof, so as to completely enclose or imbed the clip ends within the tag. Under the prevailing methods the clip is secured to the tag by crimping the ends of the clip through the tag material and clinching the same, leaving the ends of the clip exposed or adapted to be wedged outwardly so that they will protrude from the tag and be in a position to readily prick into the fabric and cause injury or damage thereto.

It is, therefore, an object of the invention to secure the clip to the tag with the prong ends of the clip engaged into the body of the tag or between ply layers thereof securely anchoring the clip within the tag material.

Another object of the invention is to provide a tag of plural ply having a fold edge from which the clip fastener extends forming an overlap for the ends of the clip anchored between the layers of the tag.

According to the present invention the prongs or limbs of the clip pierce the fold edge of a plural ply tag with the ends of the prongs engaged between the plys and bent to an angle or loop to increase its anchoring hold. The ends of the prongs are thrown out of line with the prongs at the points where the prongs pierce through the fold edge of the tag. In providing the tag of

plural ply and represented as a piece of material folded upon itself, manufacture of the tag and the application of the fastener is facilitated, for in production tags are made in strip lengths from tape material.

The invention in the preferred form is illustrated in the accompanying drawings, in which:

Figure 1 is a side elevation of a strip length of tags.

Figure 2 is a side elevation of a single tag cut from the strip length.

Figure 3 is a view illustrating the tag clip engaged over the fabric edge just prior to folding over the edge of the fabric and clip.

Figure 4 is a view showing the tag in its attached position on the fabric.

Figure 5 is a sectional view taken on line 5—5, Figure 2, illustrating the manner in which the tag clip is secured between the folds of the tag.

Referring to the drawings, 1 indicates a tag or ticket represented as a plural ply made of a paper stock of a required weight for the desired card thickness or gauge. As the present invention relates solely to the means or method employed for connecting or anchoring a wire clip fastener to the tag the description would be directed solely to the tag and its fastener as an article of manufacture rather than to the method of manufacture. The tags are usually merchandised in gang or strip form, facilitating in the use of the product in connection with price marking machines, although the tag may be featured individually.

Likewise, the structure of the clip may represent several modifications or embrace various forms so as to include the present commercial styles of clips, reference to the preferred form herein being merely used as an example of one particular type of clip with which the invention is incorporated. The invention relates primarily to the means employed for anchoring the clip to and within the tag, so that its anchoring ends are completely enclosed and securely engaged to the tag and bound by the material of the tag.

This particular style of fastener leaves ex-

posed no point of a wire which could effect injury or damage to the goods or injury to anyone handling the goods.

With the tag represented as of plural ply formed by folding the material upon itself provides a fold edge 2 selected as the top or head edge of the tag from which the clip 3 extends. The clip is preferably formed of a single length of soft or annealed wire easily folded or bent and in its normal or merchandising form comprises a pair of limbs or prongs 4—4, in approximate parallel arrangement with the ends of the wire or limbs engaged through the fold edge 2 to lie between the plies of the tag.

Each end is bent to a scroll and in relative opposing directions to extend at an angle or lateral to the limbs for increasing its anchorage hold with the tag material and between the plies thereof. The layers or plies of the tag are adhesively united for their entire area, thus binding the scroll convolutions and in a recessed capacity within the layers, rigidly securing the clip to the tag. The fold reinforces the tag edge against bodily extraction of the clip from the tag.

The limbs from the parallel disposition converge and are developed into a loop 5 extending inwardly to the tag and with a reach short of the length of the limbs to present a hook for engagement over the edge of the fabric to be ticketed. For securing the tag to the fabric after the clip has been engaged over an edge thereof, the clip with the fabric is lap-folded, hitching the clip with the tag to the goods. The clip, however, can be of a type for obtaining a friction hold similar to the clips used for fastening papers, or to any style of clip which would permit anchorage to the tag in the manner herein specified.

Having described my invention, I claim:

A tag, comprising, a body of plural ply, the material thereof folded upon itself providing a fold edge at one end and the plies adhesively united, and a hook clip extending from the body of the tag to engage about the material to be tagged and to be folded therewith for securing the clip to the material, said clip having a pair of parallel prongs engaged through the fold edge at spaced points, the ends thereof between the plies formed into scrolls for anchoring the clip to the tag.

In witness whereof, I hereunto subscribe my name.

FREDERICK KOHNLE.
